(57) **CLAIM**

The ornamental design for a vehicle tailgate panel, as shown and described.

DESCRIPTION

FIG. 1 is a front perspective view of the vehicle tailgate panel; FIG. 2 is a right side elevation view thereof; FIG. 3 is a top plan view thereof; and, FIG. 4 is a front view thereof.

The left side elevation view of the vehicle tailgate panel is omitted because the left side elevation view is identical to the right side elevation view. And the broken lines shown in the drawings depict portions of the vehicle tailgate panel that form no part of the claimed design.
